Application March 20, 1942, Serial No. 435,497

11 Claims. (Cl. 62—119.5)

This invention relates to the art of refrigeration and more particularly to a novel three-fluid absorption refrigerating mechanism and to a novel arrangement for assembling a three-fluid absorption refrigerating mechanism with a domestic refrigerator cabinet structure.

Heretofore, the common practice of the art has been to provide cabinets for domestic refrigerating machines of the three-fluid type which include vertically extending air flues along the rear wall of the cabinet structure. Such flues accommodate a heavy, bulky frame structure and house an air-cooled condenser. That part of the refrigerating mechanism which is not supported in the air flue is mounted in a mechanism compartment located beneath the food storage compartment. Certain air cooled elements are also positioned in the mechanism compartment and the whole apparatus is supported and held together by means of a heavy steel framework. It is also common practice to provide a vertically extending gas heat exchanger which is embedded in the insulation of the rear wall of the cabinet structure. In prior machines an opening is provided in the rear wall of the cabinet structure through which the cooling unit is inserted into the refrigerating compartment. A suitable panel is provided to encase the conduits passing to the evaporator structure and to close the opening provided in the cabinet therefor.

The rear flue characteristic of previous constructions is a source of great difficulty to the designer and manufacturer because such flues must be of considerable depth in order to house the condenser, framework and other mechanism which is normally placed therein. This construction adds considerable depth to the cabinet structure and renders it very difficult to design a satisfactory refrigerator cabinet within the standard depth limitations imposed upon kitchen appliances. It is also characteristic of prior constructions that the condenser is cooled by air previously heated by passage across the absorber and rectifier.

In previous constructions it has been generally thought to be necessary to place the condenser at an elevation with respect to the evaporator such that liquid refrigerant could flow by gravity from the condenser into the evaporator.

In assembling prior constructions the refrigerating mechanism and its framework has been made up into a unit together with the closure elements for the rear window opening of the cabinet. After this assembly is made the refrigerat-

ing mechanism is slid into the cabinet from the rear thereof and secured into position after which the various panels forming the boundaries of the rear air flue are attached to the cabinet structure.

Accordingly it is an object of the present invention to provide a refrigerating machine of the absorption type which is characterized by the complete absence of a flue structure extending along a vertical wall of the refrigerator cabinet, in which the framework of the refrigerating machine is reduced to a relatively light weight frame mechanism which occupies but small volume in the cabinet structure and to provide a complete refrigerating machine which utilizes the inherently great mechanical strength of certain of the parts of the apparatus to support the various parts of the apparatus in their proper relative positions without aid from auxiliary frame elements.

It is a further object of the invention to provide an absorption refrigerating machine of the three-fluid type so constructed and arranged that the condenser may be placed in the relatively cool machinery compartment which is located below the refrigerated chamber.

It is a further object of the invention to provide an absorption refrigerating machine in which the condenser and absorber are cooled by independent streams of previously unheated cooling air.

It is a further object of the invention to provide a novel means for conveying liquid refrigerant from the condenser to the evaporator.

Another object of the invention is to provide a construction in which the lean gas en route to the evaporator is placed in heat exchange relationship with rich gas discharging from the evaporator and with liquid refrigerant flowing to the evaporator.

It is a further object of the invention to provide a refrigerator including a gas heat exchanger construction which serves to exchange heat between the inert gas passing to and from the evaporator, to provide a means for conveying liquid refrigerant from the condenser to the evaporator, to provide a means for cooling liquid refrigerant en route to the evaporator and to form a support for the evaporator within the cabinet structure.

It is a further object of the invention to provide an absorption refrigerating machine construction in which the liquid refrigerant en route from the condenser to the evaporator is precooled by being passed in heat exchange rela-

tionship with the rich gas discharged from the evaporator and is further pre-cooled by an evaporative process.

It is a further object of the present invention to provide a three-fluid absorption machine in which certain parts thereof are encased in other parts of the apparatus.

Other objects and advantages of the invention will become apparent as the description proceeds when taken in connection with the accompanying drawings, in which—

Figure 1 is a side elevational view partly in section illustrating the invention assembled with a cabinet, and

Figure 2 is a sectional view of a portion of the apparatus drawn upon an enlarged scale.

Figure 3 is a side elevational view, partly in section, illustrating a modified form of the refrigerating apparatus designed and intended to be positioned in a cabinet such as that illustrated in Figure 1.

Figure 4 is a sectional view on an enlarged scale of the details of a modified form of pumping mechanism to be used in the apparatus of Figure 3.

Referring now to the drawings in detail and first to Figure 1 thereof, there is illustrated a three-fluid absorption refrigerating apparatus comprising a boiler B, an analyzer D, an air-cooled rectifier R, a tubular air-cooled condenser C, an evaporator E, a gas heat exchanger structure G, a tubular air-cooled absorber A, a solution reservoir S, a liquid heat exchanger L, a circulating fan or gas pump F which is driven by an electrical motor M. The above described refrigerating elements will be connected by suitable conduits to form a plurality of fluid circuits to be described hereinafter.

The above described system will be charged with a suitable refrigerant, such as ammonia, an absorbent therefor, such as water, and a pressure equalizing medium which is inert with respect to the refrigerant and absorbent, preferably a dense gas such as nitrogen.

A suitable heater, not shown, such as a gas or liquid fuel burner will be provided for applying heat to the boiler. The operation of the boiler heater and the motor M will be controlled by a suitable control mechanism, not shown, preferably of the type disclosed in U. S. Patent No. 2,228,343 to Curtis C. Coons, dated January 14, 1941.

The application of heat to the boiler B causes evolution of refrigerant vapor from the strong solution normally therein contained. The vapor so produced passes upwardly through the analyzer D in contact with strong solution returning to the boiler. The resulting vapor is then conveyed from the analyzer to the rectifier by way of conduit 12 and from the rectifier to the upper portion of the condenser C by way of the conduit 13.

The weak solution formed in the boiler by the generation of refrigerant vapor is conducted therefrom to the solution reservoir S by way of the conduit 15, the liquid heat exchanger L and the conduit 16 which includes a looped finned portion, as shown, for the purpose of pre-cooling the solution. The solution is then conveyed from the reservoir to the upper portion of the absorber A by means of the gas lift conduit 18 to which pumping gas is supplied from the discharge conduit 19 of the circulating fan F by means of a diversion conduit 20 which introduces the gas into the conduit 18 below the liquid level

normally therein maintained. The solution reservoir S is vented to the suction conduit 22 of the circulating fan by means of a vent conduit 23.

The lean solution supplied to the upper end of the absorber flows downwardly therethrough by gravity in counterflow relationship with a rich mixture of pressure equalizing medium and refrigerant vapor which is supplied to the lower portion of the absorber in a manner to be described. The solution absorbs refrigerant vapor from the mixture and the resulting heat of absorption is rejected to cooling air flowing over the exterior walls of the absorber conduit and the air cooling fins mounted thereon. The strong solution formed in the absorber is conveyed therefrom to the upper portion of the analyzer by way of a conduit 25, liquid heat exchanger L, and conduit 26, thus completing the absorbing solution circuit.

The lean inert gas formed in the absorber is conveyed therefrom to the inlet of the fan F by the conduit 22. After being placed under pressure in the fan F the gas is conveyed therefrom to the lower portion of the evaporator E by means of the conduit 19, the outer path 30 of the gas heat exchanger G and the evaporator gas supply conduit 31.

Liquid refrigerant is supplied from the condenser to the evaporator liquid supply conduit 32 in a manner to be described hereinafter. The conduit 32 is U-shaped to form a gas sealing liquid trap.

The evaporator may be of any desired type. However, it is preferably of the type in which the inert gas and liquid refrigerant are supplied to the bottom of the evaporator and in which the liquid refrigerant is circulated upwardly through the evaporator as it is evaporating by the frictional dragging action of a relatively high velocity stream of inert gas.

After traversing the evaporator the rich inert gas is conveyed therefrom to the bottom portion of the absorber by way of conduit 33, the inner gas path 34 on the gas heat exchanger and the gas conducting conduit 35. The inert gas refrigerant vapor mixture then flows upwardly through the absorber in contact with the absorbing solution in the manner heretofore described.

The gas heat exchanger construction also houses a mechanism for conveying liquid refrigerant from the condenser to the evaporator. As is clearly shown in Figure 2 the gas heat exchanger is composed of three concentric cylinders 40, 41 and 42. The outer space 30 between the cylinders 40 and 41 is the lean gas path of the heat exchanger, the next space 34 between the walls 41 and 42 is the rich gas space of the heat exchanger and the inner space 43 houses the condensate elevating mechanism. The conduits 19 and 31 open through the wall 40 into the space 30. The conduits 33 and 35 open through the end plate 44 and the wall 41 into the rich gas space 34. End plates 45 and 46 serve to seal the space 43.

The condensate which is formed in the condenser flows from the bottom portion thereof into a gas lift elevating pipe 50 which discharges into a chamber 51 formed in the bottom portion of the compartment 43 of the heat exchanger G by a light intermediate partition 52. Pumping gas is introduced into the conduit 50 by means of a conduit 53 which receives pumping gas from the discharge conduit 19 of the fan by means of a conduit 54. The wall 42 of the gas heat exchanger is provided with a vent opening 55 to

discharge the pumping gas into the rich gas chamber 34 of the heat exchanger. The liquid refrigerant elevated through pipe 50 collects in the lower portion of the chamber 51 and is elevated into the next higher chamber in the heat exchanger by means of a gas lift pump 56 which receives pumping gas through a conduit 57 which is connected to the gas supply conduit 54.

It will be seen that the conduit 54 extends upwardly through the chamber 43 of the heat exchanger until the same terminates at a connection to the highest gas lift pump 58 which receives liquid from a lower gas lift pump 56b, that is, the liquid refrigerant is elevated in steps by a series of gas lift pumps extending upwardly through the gas heat exchanger G to the point at which the pump 58 discharges into a chamber 59 which is drained by the evaporator supply conduit 32 and is vented through an opening 60 to the rich gas portion of the gas heat exchanger.

In each case pumping gas is introduced into the pumping conduit below the liquid level normally maintained therein to provide an adequate depth of immersion for operation of the pump.

Therefore it will be seen that the liquid refrigerant is elevated from the bottom portion of the condenser into the chamber 59 through the gas lift elevating pump 50, the gas lift elevating pump 56, and a series of intermediate but identical gas lift elevating devices indicated generally at 65 in the broken portion of the gas heat exchanger and terminating in the gas lift pump 58 which discharges into the chamber 59.

In order to facilitate operation of the gas lift pump and to purge the condenser of non-condensable material which may find its way thereinto a vent conduit 61 is provided to connect between the lower portion of the condenser but above the level of liquid collecting therein for operation of the gas lift pump 50 and the gas conduit 35 which is subjected substantially to the suction pressure of the circulating fan F.

As may readily be seen in Figure 1 the apparatus is assembled with a cabinet. A lower base assembly is provided which comprises a base element 70 which rests upon the floor and which is of open construction to allow free access of cooling air into the space thereabove. A channel and angle iron box frame indicated generally at 71 and is provided for supporting the refrigerat-

ing mechanism.

The boiler, analyzer, liquid heat exchanger assembly is encased in a body of insulating material 72 and rests upon the frame 71 at the rear portion thereof. The absorber is positioned in the front, upper portion of the space defined by the frame and extends downwardly and rearwardly therein. The condenser is positioned rearwardly of the absorber and is sloped at a sharper angle. By this construction cooling air which flows into the chamber 73 defined by the box frame 71 has free access to the absorber and condenser and each of these elements is cooled by air which has not previously passed over an air cooled element except for the slight amount of heat which will be imparted to some of the air by the absorption solution precooler. The air stream travels in a generally vertical path until the same has passed across the condenser and the absorber after which the stream flows to the rear across the rectifier and discharges at the rear of the box frame in a manner to be described more fully hereinafter.

Due to the fact that refrigerating systems of this type must withstand high static pressures, 75

the refrigerating mechanisms themselves are all rigidly welded together and are all constructed of heavy material whereby the same inherently possess great mechanical strength. To support the refrigerating mechanism on the box frame, various portions of the apparatus are secured to adjacent parts of the box frame by strap irons, bolting, welding, brazing and the like in order that the refrigerating mechanism and the box frame will form a rigid whole. A typical connection is shown at 74. As a result of this construction the box frame encases the boiler, analyzer, liquid heat exchanger, rectifier, absorber, condenser, solution reservoir, circulating fan and drive motor and the gas heat exchanger evaporator structure projects upwardly therefrom.

The rigidity of the various gas and liquid conduits and their connections to the box frame form a structure possessing such inherent mechanical strength that the evaporator and gas heat exchanger require no other support than that required by their connections to the box frame and to the refrigerating mechanism so that the evaporator is suspended from the gas heat exchanger which is in turn supported by the lower box frame and refrigerating mechanism.

The box frame also supports an insulated panel 76 which is provided with beveled edges as indicated at 77 and forms the bottom closure of the cabinet structure.

The chamber 73 is provided with a suitable closure element 78 at the front thereof which will be suitably decorated to conform to the exterior finish of the cabinet structure.

The entire refrigerating mechanism, the base member 70, the box frame, closure plates 78 and insulated bottom wall structure 76 of the cabinet form a complete operative unit. The base element 70 and box frame form the sole supporting means and framework for this unit other than the inherent rigidity and mechanical strength of the refrigerating mechanism itself.

The gas heat exchanger extends vertically from the chamber 73 through the panel 76 and forms the sole supporting means for the evaporator.

A cabinet structure indicated generally at 80 comprises insulated top, rear and side and front vertical walls and an insulated closure 81 which is adapted to provide access to the interior 82 of the cabinet by means of a suitable opening formed in the insulated front wall of the compartment. The lower edges of the vertical walls of the cabinet 80 are beveled as is indicated at 84 in order that the same may engage the beveled edges 77 of the panel 76, thus forming sealed joints at that point. If desired, a suitable gasket of rubber or like material may be provided in a recess 83 in the panel 76 in order to insure that this joint shall be absolutely airtight.

The evaporator will be enclosed in a suitable housing indicated generally at 85 and a food-stuffs refrigerating drawer 86 may be supported on top of the evaporator structure for refrigerating meats and the like.

In order to dispose of waste products of combustion from the boiler heater a waste products of combustion flue 88 is provided which extends from the outlet of the boiler flue 89 vertically along the rear wall of the base structure and also along the rear wall of the cabinet 80 to a point adjacent the top thereof in order to distribute waste products of combustion above the cabinet level. This flue will preferably have a very small

depth in a direction corresponding to the direction of the depth of the cabinet though it may be wide as compared with its depth. Preferably the boiler will be located in one corner of the chamber 73 so as to remove the same from a path of cooling air flowing over the air cooled elements of the apparatus which will bring the element 88 adjacent one corner of the apparatus.

In assembling the above construction the refrigerating mechanism, base elements 70, box frame 71, panel 76 are assembled as a complete unit at which time the same may be tested. After proof of satisfactory operation by tests, the cabinet mechanism 80 is simply lowered over the aforesaid assembly until the beveled edges 84 and 77 engage after which the cabinet elements 80 will rest directly upon the elements 76 and upon the box frame 71. If desired, suitable bolts may be provided to bolt the vertical panels of the cabinet 80 to the top elements of the box frame.

The above described construction is characterized by the total absence of a vertical air flue structure projecting rearwardly of the cabinet. All air cooled portions of the apparatus are positioned beneath the food storage compartment of the refrigerator and the only element projecting rearwardly of the normal rear wall thereof is the very shallow products of combustion flue conduit 88.

The flue conduit 88 is so shallow that there is very little likelihood that the same will ever be pushed against the wall as the chair board at the base of the wall will space the rear of the refrigerator far enough from the wall proper to provide ample clearance for the element 88 and to provide a space from which cooling air heated by passage over the absorber, condenser, rectifier and solution pre-cooler and the various conduits in the chamber 73 may freely pass into the room.

Referring now to Figures 3 and 4 there is disclosed a modified form of the invention. The major elements of this form of the invention are identical with those described above in detail in connection with Figures 1 and 2, hence parts of the apparatus illustrated in Figures 3 and 4 corresponding to parts of the apparatus described above in connection with Figures 1 and 2 are given the same reference characters primed.

This form of the invention is substantially identical to the form of the invention described above in connection with Figures 1 and 2 except with respect to the location of the circulating unit for the inert gas and the location and arrangement of the means provided to supply the liquid refrigerant to the evaporator.

Referring now to Figure 3, the condenser C' is connected to supply liquid refrigerant to a pump reservoir 100 through a conduit 101. The upper portion of the pump reservoir is vented by means of a conduit 102 to the rich gas conduit 35' which is connected to the absorber and is under a low static pressure as the absorber is connected to the suction inlet of the circulating fan 103 through the conduit 22' (see Figure 4).

The gas circulating fan 103 is encased within a housing 105 which is provided with a dividing partition 106 separating the same into a chamber 107 for the fan and a chamber 108 which houses a drive mechanism for a liquid refrigerant pumping device. The shaft 110 of the motor M' carries the fan 103 and is extended into the chamber 108 through the suction eye of the fan in the partition 106. The end of the shaft 110 in chamber 108 carries a cam 112 which contacts the upper end of a cam follower shaft 113. The cam

follower shaft 113 and its extended reduced portion 114 extends through a bearing sleeve 115 which is hermetically sealed to the housing 105 and to the reservoir 100. The upper portion of the sleeve 115 is enlarged as illustrated to house a spring 117 which encompasses the upper portion of the reduced section 114 of the follower and bears at its upper end against the shoulder 118 formed at the junction point of the portions of the follower of different diameter. The spring 117 serves to maintain the follower 113 in contact with the cam 112.

The sleeve 115 extends through the reservoir 100 and is in open communication with conduit 120. The portion of the sleeve 115 within the reservoir 100 is provided at its lower portion with diametrically opposed cut-outs 121. The reduced portion of the follower 114 opposite the cut-outs 121 is provided with a transverse bore 122 which is in communication with an axial bore 123 extending to the lower end of the reduced portion 114 of the follower. A small perforated cage 124 is securely attached to the lower end of the follower 114 and a suitable ball check 125 is mounted in the cage 124 in position to seal the bore 123 when the ball is in contact with the end of follower 114.

The conduit 120 communicates with a ball check housing 128 which is provided with a ball check mechanism 129 as illustrated. The upper end of the housing 128 is in communication with a liquid refrigerant conduit 130.

The conduit 130 extends upwardly through the inner passage 132 of a gas heat exchanger 133. The inner passage of the gas heat exchanger is defined by the inner shell 132 which in turn passes through the outer passage of the gas heat exchanger defined by the outer shell 134.

The inner shell of the gas heat exchanger 133 communicates at its upper end with the rich gas discharge conduit 33' of the evaporator E' and at its lower end with the conduit 35' which conveys the rich gas to the lower end of the absorber A'. The pipe 130 discharges at its upper end into a chamber 136 defined in the upper portion of the shell 132 by a partition 137. The liquid refrigerant discharged from the pipe 130 into the chamber 136 is conveyed therefrom to the evaporator by the conduit 32'.

This form of the invention will be secured to a box frame and will be associated with a cabinet similarly to the form of the invention previously described. As before, the various parts of the refrigerating mechanism per se are of sufficient strength to provide a support for the gas heat exchanger 133 and for the evaporator and its associated conduits. Figure 3 illustrates the arrangement of the parts for association with a cabinet structure like that shown in Figure 1.

In the operation of this form of the invention liquid refrigerant flows from the condenser into the reservoir 100. The motor M' imparts a reciprocating movement to the cam follower 113-118 against the bias of the spring 117 through the action of the shaft 110 and cam 112. As the lower end of the follower 114 reciprocates liquid is pumped therefrom into the conduit 130 in the following manner: On the downstroke of the follower 114 the ball check 125 is forced against the lower end of the bore 123, thus closing the same, and a quantity of liquid refrigerant in the conduit 120 is forced past the ball check 129 into chamber 12 and conduit 130. On the upstroke of the follower 114 under the bias of spring 117 the ball check 129 seats in the cham-

ber 128 and prevents liquid from passing from chamber 128 into conduit 120. Also on the up-stroke the ball check 125 drops into the cage 124 in the position shown in Figure 4 and liquid refrigerant flows through the bore 122 and bore 123 into the conduit 120. In this manner liquid refrigerant is pumped from the reservoir 100 upwardly into the chamber 136 from which it flows through the U-shaped trap 32' into the bottom portion of the evaporator E.

In this form of the invention like that described in Figures 1 and 2 a single motor element M' operates to circulate the inert gas, to circulate the absorbing solution, to elevate liquid refrigerant into the evaporator and to circulate the liquid refrigerant through the evaporator by the frictional drag of the inert gas flowing therethrough.

It is also characteristic of this form of the invention that the liquid refrigerant flowing through the conduit 130 is brought into intimate heat transfer relationship with the cold rich mixture of inert gas and refrigerant vapor flowing downwardly through the shell 132, whereby the liquid is appreciably pre-cooled before being supplied to the evaporator.

The present invention provides very efficient cooling as both the absorber and condenser are individually cooled by air taken from adjacent the floor of the room where the coolest available air is to be found. Due to the fact that the heat is applied to the air at a very low point in the cabinet structure the chimney effect is large and the velocity of cooling air flow through the mechanism compartment is high as compared with previous structures.

In the constructions herein disclosed the gas heat exchanger serves as a supporting element for the evaporator and a part of the framework of the refrigerating mechanism per se. This element also functions as a triple heat exchanger and pre-cooler element. The rich inert gas discharging from the evaporator, the lean inert gas discharging from the absorber and the condensate en route from the condenser to the evaporator are all brought into heat exchange relationship in a triple heat exchanger structure and the condensate is brought substantially to the temperature of the evaporator before being supplied thereto because of the fact that the same is cooled by the cold, rich inert gas discharging from the evaporator and passing through the passageway which surrounds the condensate elevating mechanism.

In the form of the invention illustrated in Figures 1 and 2, the condensate is further cooled by evaporation which may occur in the various pump chambers housed within the space 43 in which the condensate is brought into contact with a relatively small amount of inert gas.

The pre-cooling thus affects the design, construction and operation of the evaporator and promotes uniformity of the operation in all parts of the evaporator which serves to promote the efficiency of the apparatus and to insure that material placed therein will be uniformly refrigerated.

By reason of the construction herein disclosed the cabinet proper is relieved of all stress loads and mechanical parts and need not be designed to receive any mechanical parts other than simply to enclose the evaporator and the vertically extending gas heat exchanger and need not be provided with any openings to be filled in a patch-

work manner after the assembly of the apparatus.

It is particularly characteristic of the present invention that all heat rejecting portions of the apparatus are enclosed in the lower part of the cabinet beneath the food storage compartment and lying within the projected area of the food storage compartment whereby the depth of the cabinet structure as a whole with its associated refrigerating mechanism need not exceed that required for the food storage compartment and its insulating walls. Also by placing all heat rejecting portions of the apparatus in the very lowest portion of the cabinet the rejection of heat is facilitated and all the heat rejecting elements are supplied with cold air taken from adjacent the floor of the room housing the refrigerating mechanism and the maximum chimney effect is available for causing air to traverse these elements and to carry the heat away therefrom.

While the invention has been illustrated and described herein in considerable detail, it is not to be limited thereto but various changes may be made in the construction, arrangement, proportion of parts without departing from the spirit of the invention or the scope of the appended claims.

I claim:

1. An absorption refrigerating assembly comprising an open base and frame structure; an absorber, a generator and a condenser supported by and within said frame structure; an evaporator positioned at an elevation above said frame structure, a vertically extending gas heat exchanger connected to provide for flow of a gas between said evaporator and said absorber and forming the sole supporting means for said evaporator, means connecting said absorber and said generator for circulation of absorption solution therebetween, and means for conducting refrigerant vapor produced in said generator to said condenser and for lifting refrigerant liquid from said condenser to said evaporator.

2. In a refrigerator, a cabinet structure including an insulated refrigerating chamber and an air cooled mechanism chamber underlying said refrigerating chamber; a refrigerating apparatus associated with said cabinet structure comprising an evaporator in said refrigerating chamber, an air cooled condenser and an air cooled absorber in said mechanism chamber, a generator in said mechanism chamber, a vertically extending gas heat exchanger extending from said mechanism chamber into said refrigerating chamber, means connecting said gas heat exchanger to said evaporator for conveying inert gas to and from said evaporator, means connecting said gas heat exchanger to said absorber for conveying inert gas to and from said absorber, means connecting said generator and said absorber for circulation of absorption therebetween, means for conveying refrigerant vapor from said generator to said condenser, means for lifting refrigerant liquid from said condenser to said evaporator, and frame means in said mechanism chamber rigidly secured to said refrigerating apparatus, said refrigerating apparatus and said frame means being so constructed and arranged that the same forms a rigid whole lying within the horizontal dimensions of said refrigerating chamber.

3. In a refrigerator, a cabinet structure including an insulated refrigerating chamber and an air cooled mechanism chamber underlying said refrigerating chamber; a refrigerating ap-

paratus associated with said cabinet structure comprising an evaporator in said refrigerating chamber, an air cooled condenser and an air cooled absorber in said mechanism chamber, a generator and a power operated gas circulator in said mechanism chamber, a gas heat exchanger extending from said mechanism chamber into said refrigerating chamber, means connecting said gas heat exchanger to said evaporator for conveying inert gas to and from said evaporator, means including said gas circulator connecting said gas heat exchanger to said absorber for conveying inert gas to and from said absorber, means connecting said generator and said absorber for circulation of absorption solution therebetween, means for conveying refrigerant vapor from said generator to said condenser, gas operated means for conducting refrigerant liquid from said condenser to said evaporator, means for supplying gas to said gas operated means, said refrigerant liquid conveying means extending from said condenser to the level of said evaporator through said gas heat exchanger, and frame means in said mechanism chamber rigidly secured to said refrigerating apparatus, said refrigerating apparatus and said frame means being so constructed and arranged that the same forms a rigid whole lying partially within and partially beneath said refrigerating chamber.

4. Absorption refrigerating apparatus comprising an absorber, a generator, means connecting said absorber and said generator for circulation of absorption solution therebetween, a condenser connected to receive refrigerant vapor from said generator, an evaporator positioned at an elevation above said condenser, and said absorber, a gas heat exchanger construction having a central space surrounded by a pair of concentric gas flow passageways, means connecting said evaporator and said absorber for circulation of inert gas therebetween including said pair of concentric gas flow passageways and pumping means including means extending through said central space of said gas heat exchanger for elevating refrigerant liquid from said condenser to said evaporator.

5. Absorption refrigerating apparatus comprising an absorber, a generator, means connecting said absorber and said generator for circulation of absorption solution therebetween, a condenser connected to receive refrigerant vapor from said generator, an evaporator positioned at an elevation above said condenser and said absorber, a gas heat exchanger having a central passageway surrounded by a pair of gas conducting passageways, means connecting said evaporator and said absorber for circulation of inert gas therebetween including a gas pump arranged to place said inert gas under pressure and said gas conducting passageways of said gas heat exchanger, a plurality of serially connected gas lift pumps extending through said central passageway for conveying refrigerant liquid from said condenser to said evaporator, means for supplying pumping gas placed under pressure by said gas pump to said gas lift pumps, and means for admitting the used pumping gas from said central passageway to one of said gas conducting passageways.

6. An air cooled absorption refrigerating machine including a cabinet structure having an insulated refrigerating compartment and an air cooled mechanism compartment underlying said refrigerating compartment and having no hori-

zontal dimension in excess of the horizontal dimensions of said insulated refrigerating compartment; an air cooled refrigerating mechanism of the three-fluid absorption type associated with said cabinet structure and having all parts thereof positioned within said compartments, said refrigerating apparatus including an evaporator positioned within said refrigerating compartment, and air cooled heat rejecting parts in said mechanism compartment inert gas conveying means for said evaporator extending from said refrigerating compartment to said mechanism compartment and forming the sole supporting means for said evaporator, and means for conveying refrigerant liquid from apparatus in said mechanism compartment to said evaporator and extending through said inert gas conveying means, and a fluid circulator in said mechanism compartment arranged to produce flow of inert gas and refrigerant liquid through said inert gas conveying means.

7. In a refrigerator assembly; a base structure constructed to allow flow of cooling air therethrough, an insulated panel forming the top wall of said base structure; a three-fluid air cooled absorption refrigerating apparatus of the absorption type utilizing a power driven device for placing an inert gas under pressure associated with and supported on said base structure, said refrigerating apparatus being positioned within said base structure with the exception of an evaporator positioned above said insulated panel, a heat exchanger structure extending from the interior of said base structure to said evaporator and arranged to convey inert gas to and from said evaporator, said heat exchanger structure serving as the sole supporting means for said evaporator, a plurality of serially connected gas lift pumps extending through said heat exchanger structure and arranged to elevate refrigerant liquid from the level of said base structure to said evaporator, and means for conducting gas placed under pressure by said power driven device to said gas lift pumps for operating the same.

8. That improvement in the art of absorption refrigerating systems of the type utilizing a refrigerant, an absorbent for the refrigerant and a gaseous medium which is inert with respect to the refrigerant and the absorbent, which includes the steps of applying heat to a solution of the refrigerant in the absorbent to liberate refrigerant therefrom, liquefying the said refrigerant vapor, placing said gaseous medium under pressure and circulating the same between a place of evaporation and a place of absorption, subjecting the said liquefied refrigerant to said gaseous medium under pressure to convey the same to said place of evaporation and to pre-cool the liquefied refrigerant by evaporation into said gaseous medium and transferring heat between gaseous medium flowing from said place of evaporation, gaseous medium flowing to said place of evaporation and liquefied refrigerant flowing to said place of evaporation.

9. Absorption refrigerating apparatus comprising an absorber, a generator, means connecting said absorber and said generator for circulation of absorption solution therebetween, a condenser connected to receive refrigerant vapor from said generator, an evaporator positioned at an elevation above said condenser and said absorber, a gas heat exchanger construction having a central space surrounded by a pair of concentric gas flow passageways, means includ-

ing said concentric gas flow passageways connecting said evaporator and said absorber for circulation of inert gas therebetween, and means for elevating refrigerant liquid from said condenser to said evaporator including means extending through said central space of said gas heat exchanger.

10. In a refrigerator; a cabinet structure comprising an insulated refrigerating chamber and a mechanism chamber wholly underlying said refrigerating chamber, said mechanism chamber being open at the rear of said cabinet structure for egress of cooling air and at the bottom thereof for entrance of cooling air; an absorption refrigerating mechanism including a condenser, a generator, an absorber and an evaporator; means connecting said condenser, generator, absorber and evaporator in circuit; means supporting said generator, absorber and condenser in said mechanism chamber and said evaporator in said refrigerating chamber, said absorber comprising a tubular finned conduit lying in a plane inclined slightly to the horizontal and arranged in the forward portion of said mecha-

nism chamber, said condenser comprising a tubular finned conduit lying in a plane inclined to the vertical and positioned in said mechanism chamber rearwardly of said absorber, and means for elevating refrigerant liquid from said condenser to said evaporator.

11. Absorption refrigerating apparatus comprising an absorber, a generator, means connecting said absorber and said generator for circulation of absorption solution therebetween, a condenser connected to receive refrigerant vapor from said generator, an evaporator positioned at an elevation above said condenser and said absorber, a gas heat exchanger construction having a central space surrounded by a pair of concentric gas flow passageways, means connecting said evaporator and said absorber for circulation of inert gas therebetween including said pair of gas flow passageways and power operated fluid propulsion means having a fluid conveying part extending through said central space for elevating refrigerant liquid from said condenser to said evaporator.

DALE C. GERBER.
